ABSTRACT

A liquid flowing through a restricted throttling passage is heated by the energy of an electric signal that it is desired to convert to a hydraulic signal, and the resulting increase in the temperature and the fluidity of the liquid causes increased flow through the passage, the increase constituting the hydraulic signal. Use of the hydraulic signal for controlling a slide valve is illustrated.

ELECTRO-HYDRAULIC TRANSDUCER

This invention relates to transducers, and particularly to an electro-hydraulic transducer arrangement which converts an electric signal into a hydraulic signal, and to a method of converting an electric signal into a hydraulic signal by means of such an arrangement.

It is known to convert an electric signal into a hydraulic signal by passing a liquid through a throttling zone whose effective flow section is varied by means of an electromagnetic device operated in response to the electric signal that it is desired to convert. The resulting change in the flow rate of the liquid through the throttling zone constitutes a hydraulic signal which may be employed for controlling a valve or amplifier.

The known devices rely on moving parts and are subject to the limitations and shortcomings inherent in mechanical devices. It is an object of the invention to provide an electro-hydraulic transducer arrangement capable of operating without solid moving elements.

According to one of its more specific aspects, the invention provides a restricted throttling zone with electrically operated heating means which respond to the electric signal to be converted for varying the temperature, and thereby the viscosity or fluidity of a liquid supplied to the throttling zone under pressure. The liquid is guided through the zone in a predominantly laminar flow pattern. The change in viscosity produces a corresponding change in the flow rate of the liquid through the throttling zone, and the change in the flow rate provides the desired hydraulic signal.

According to another aspect, the invention resides in a method of converting an electric signal to a hydraulic signal in which a liquid is supplied under pressure to a restricted throttling zone. The energy of the electric signal is converted in the zone to thermal energy, and the latter is transmitted to the liquid in the zone, whereby the temperature and viscosity of the liquid are changed, and its flow rate through the throttling zone is increased, the increase in flow rate constituting the desired hydraulic signal.

Other features, additional objects, and many of the attendant advantages of this invention will readily become apparent as the invention becomes better understood by reference to the following detailed description of preferred embodiments when considered in connection with the appended drawing in which:

FIG. 1 shows a first transducer arrangement of the invention in elevational section;

FIG. 2 illustrates the device of FIG. 1 in section on the line II — II;

FIG. 3 shows another transducer arrangement of the invention in elevational section;

FIGS. 4, 5, and 6 respectively illustrate the device of FIG. 3 in section on the lines IV—IV, V—V, and VI—VI;

FIGS. 7 and 8 illustrate a modified transducer in views corresponding to those of FIGS. 1 and 2 respectively;

FIGS. 9 and 10 illustrate two additional transducer arrangements of the invention in views corresponding to that of FIG. 2;

FIG. 11 shows yet another transducer arrangement in elevational section;

FIG. 12 shows the device of FIG. 11 in fragmentary section on the line XII—XII;

FIG. 13 illustrates a further transducer arrangement of the invention in elevational section;

FIG. 14 is a view of the device of FIG. 13 in fragmentary section on the line XIV—XIV;

FIG. 15 is a sectional elevation of a valve operated by a transducer of the invention;

FIG. 16 shows a portion of the apparatus of FIG. 15 in an exploded perspective view on a larger scale;

FIG. 17 shows yet another transducer arrangement of the invention in fragmentary elevational section on the line XVII—XVII in FIG. 18;

FIG. 18 illustrates the apparatus of FIG. 17 in section on the line XVIII—XVIII;

FIG. 19 is a diagram of a modification of the device of FIG. 17; and

FIG. 20 shows a modification of the devices of FIGS. 17 to 19 on a larger scale.

Referring now to the drawing in detail, and initially to FIGS. 1 and 2, there is seen a particularly simple transducer arrangement of the invention. A cylindrical metal tube 1 of limited electrical conductivity is secured at one end by a solder joint 2 in a relatively heavy mounting flange 3. The other end of the tube 1 is soldered to a lug 4 attached to a cable 5.

The tube 1 may consist of nickel-chromium or nickel-chromium-iron alloy of the type commonly employed in electric heating elements, but preferably consists of a titanium alloy containing at least 80% titanium or a zirconium alloy containing at least 50 percent zirconium, the titanium and zirconium alloys combining high electrical resistance with low heat capacity.

The steel flange 3 is normally fastened to a grounded metal object, and the liquid whose flow velocity is to be controlled is supplied to an orifice of the tube 1 at a pressure at least sufficient to cause uniform flow through the tube 1 at ambient temperature. The flow pattern in the smooth, cylindrical bore of the tube 1 is practically laminar. The flow rate through the tube 1 is controlled by an electric signal current which is passed longitudinally through the wall of the tube 1 from the cable 5 to ground, the lug 4 being supported in the air by the tube 1, and thereby electrically insulated.

The current passing through the tube 1 heats the latter and the liquid in the tube. The resulting temperature increase of the liquid, typically hydraulic fluid or oil, decreases the viscosity of the liquid, and the flow rate through the throttling zone provided by the tube 1 is increased. The hydraulic signal constituted by the increase in flow rate may be used for controlling suitable devices as will presently become apparent.

FIGS. 3 to 6 show a modification of the transducer arrangement of FIGS. 1 and 2 in which the cross section of a tube 1', otherwise closely similar to the tube 1, gradually varies from a circle at the tube end soldered to a flange 3' to a flattened loop at the end soldered to a lug 4'. For equal electric input and under otherwise equal conditions, the device of FIGS. 3 and 4 produces a greater change in the flow velocity or flow rate of a liquid than that described above. The change is commensurate to the ratio between the heating surface and the cross sectional area of the liquid.

The transducer arrangement illustrated in FIGS. 7 and 8 differs from that illustrated in FIGS. 1 and 2 by a tube 1''' of uniform cross section similar to that shown in FIG. 6. Liquid flows through the tube 1''' as a relatively thin ribbon. The flattened tube offers relatively little resistance to internal liquid pressure and is therefore reinforced by circular discs 6 perpendicular to the tube axis and soldered to the tube 1''' in axially

spaced relationship. The discs 6 also constitute cooling ribs on the tube 1''' which hasten return of the liquid temperature in the tube to ambient temperature as soon as the electric heating signal is interrupted.

A similar cooling effect can be achieved in the manner illustrated in FIG. 9 which shows only the tube 1 of the first-described embodiment spacedly enclosed in a jacket 7 through which a cooling fluid may be passed as indicated by curved arrows. The starting temperature of the liquid in the throttling tube may thus be selected at will and is independent of the ambient temperature.

While the liquid temperature in the devices of FIGS. 7 to 9 is quickly brought back to the starting temperature as soon as the electric signal is discontinued, and the flow rate of the liquid is correspondingly returned to its starting value, FIG. 10 shows an arrangement, identical with that of FIGS. 1 and 2, as far as not explicitly shown otherwise, in which the liquid flow rate responds with only a minimal delay to the application of an electric heating signal.

The tube 1 is mounted coaxially in a glass tube 8, and the annular space between the tubes 1, 8 is evacuated. Thermal losses from the tube 1 are essentially limited in this arrangement to insignificant radiation losses, and the flow rate through the throttling tube 1 quickly responds to an applied electric signal.

In the devices described so far, the tube which guides the liquid through the throttling zone consists of electrically conductive material and also functions as a heating element. This arrangement is structurally relatively simple, and heat transfer through the relatively large tube wall is effective. The response of the transducer is inherently somewhat slow because the heating element also performs structural functions and must be made heavy enough to withstand the internal hydraulic pressure, normally much higher than atmospheric pressure. Even with the use of materials of constructions having low heat capacity, a lag in response is unavoidable. It is also difficult to produce sufficiently uniform tubing in the capillary dimensions (1 mm² flow section or less) in which the throttling tubes of the invention are most useful.

The response of the transducer arrangement to the electric input signal can be hastened by assigning the guiding and heating functions to separate structural elements, that is, by installing a heating element coaxially in the conduit which guides the liquid flow in a predominantly laminar pattern. The thermal capacity of the heating element can be reduced to an insignificant value in such an arrangement. Nickel-chromium, nickel-chromium-iron, titanium alloys, zirconium alloys, and the like, may be employed for the heating elements as discussed above.

In the transducer arrangement shown in FIGS. 11 and 12, the throttling passage is partly constituted by a bore 11 in a heavy glass plate 12 which thermally insulates the liquid flowing through the bore 11. Metal washers 14a, 14b axially aligned with the bore 11 are fastened to the opposite surfaces of the plate 12 and carry respective metal brackets 13a, 13b which have free ends axially offset from the orifices of the throttling passage in the washers 14a, 14b. A flat ribbon 10 of resistance wire is held under slight tension in the throttling passage between solder joints on the brackets 13a, 13b to which the electrical signal is applied by cables in a conventional manner, not shown.

Because of the relatively small heating surface of the ribbon 10, the application of the device shown in FIGS. 11 and 12 is limited, and only small changes in the temperature of hydraulic fluid or oil passing through the bore 11 can be achieved under many conditions.

Better heat transfer is obtained in the device shown in FIGS. 13 and 14, identical with that described in the preceding paragraphs except for a heating element 10' which is starshaped in cross section and thus provides a more favorable heating surface-to-flow section area ratio than the ribbon 10.

FIGS. 15 and 16 illustrate the application of the aforescribed transducer arrangements to the control of a hydraulic valve. In these Figures, an externally heated throttling conduit is being shown by way of Example as in FIGS. 1 to 10. It will be understood, however, that an internally heated throttling passage may be provided in the device shown in FIGS. 15 and 16 without significantly affecting the operation of the apparatus.

Referring initially to FIG. 15, there is seen a valve casing 26 which receives a slide valve 15 in a stepped cylindrical bore. The valve controls flow of hydraulic fluid between a supply conduit 25, two operating conduits 22, 23 and a return conduit 24. A pump, not shown, withdraws returned fluid from a sump connected to the conduit 24 and delivers it to the conduit 25 at an elevated pressure P. In the illustrated neutral position of the valve 15, both operating conduits 22, 23 are blocked. When the valve moves toward the left, as viewed in FIG. 15, the operating conduit 22 is connected to the supply conduit 25, and the operating conduit 23 is vented to the non-illustrated sump through the return conduit 24. The flow in the operating conduits 22, 23 is reversed when the valve moves toward the right from the illustrated position. The valve arrangement described so far is entirely conventional.

The narrow end of the stepped cylindrical bore in the valve casing 26 is permanently connected with the conduit 25, and the full pressure of the hydraulic fluid acts on the smaller end face 16 of the valve 15. In order to hold the valve 15 in the illustrated position, the fluid pressure on a piston 17 of the valve 15 in the larger end of the stepped bore must assume a smaller value P_c, P and P_c being related as the areas of the effective piston face of the piston 17 and the end face 16.

The larger end of the stepped valve bore is connected with the supply conduit 25 by an adjustable trimmer throttle 19 and by a needle valve 20 threadedly mounted on the casing 26 and projecting into the orifice of an axial bore of the valve 15. The large end of the stepped bore in the casing 26 is connected with the return conduit 24 by a throttling tube 18 of the invention and an insulating tube 18'. The flow rate through the tube 18 may be changed by increasing or decreasing the output current of a signal amplifier 21 to the insulated end and to the grounded end of the tube 18.

The trimmer 19 is set in such a manner that no fluid flows through the needle valve 20 as long as the tube 18 is heated to an intermediate value. When the tube 18 is heated further, the pressure P_c can be maintained only by increased flow of fluid through the needle valve 20, and the valve 15 moves from the illustrated position toward the right to provide an adequate flow section at the needle valve 20. The opposite effect is achieved by reducing the heating current.

The trimmer valve 19 is shown in more detail in FIG. 16. Its base plate 30 is normally bolted to the valve casting 26. A capillary tube 27 is sealed by soldering in two passages 28, 29 of the base plate 30 which communicate with the supply conduit 25 and the large end of the stepped valve bore in the installed throttle 19. The tube 27 is coiled in more than one turn about a threaded stud upwardly extending from the base plate 30. A washer 33 may be lowered on the tube 27 by means of a nut 32 engaging the stud 31 elastically to deform the tube 27 and thereby to reduce the effective flow section of the same.

When the transducer arrangements of the invention are provided with throttling tubes whose electrical resistance converts the electrical energy of an applied signal to thermal energy, it has been found advisable to protect the sensitive tubes against an electrical, and thus also a thermal overload.

A suitable protection arrangement is shown in FIGS. 17 and 18. The tube 41 expands mainly longitudinally when heated. It is fixedly attached by one longitudinal end to a grounded, conductive support 42 formed with a supply bore 42a and a discharge bore 42b of substantially greater flow section than the throttling tube 41 with which the communicate. The other longitudinal end is soldered to a lug 43 held in a fixed position on the support 42 by an interposed wafer 44 of insulating material. Heating current is supplied to the tube 41 by a cable 45 on the lug 43 and the ground connection of the support 42. Liquid flows through the tube between the bores of the support 42 and of the lug 43.

In the initially installed condition, the center of the tube 41 is laterally offset from a straight line through the two ends by a small amount. When heated by the passage of current, the tube 41 buckles as shown in broken lines at 41' to cut the beam 46 of a light source 47 which is directed toward a photo-electric cell 47. The cell is arranged in circuit with a relay, not shown, which interrupts the electric heating signal fed to the tube 41 in a conventional manner evident from FIG. 19.

FIG. 19 diagrammatically illustrates a mechanical equivalent of the photoelectric safety switch arrangement described with reference to FIGS. 17 and 18. buckled, buckles, the tube 41 engages the actuating element 52 of a switch 53 and thereby interrupts the output circuit of an amplifier 51 which supplies heating current. The arrangement of FIG. 19 is somewhat less reliable than that of FIGS. 17 and 18 because of the use of moving mechanical elements, and the afore-described safety arrangement is preferred.

The distance between the two fastened ends of the tube 41 must be maintained constant for a reproducible buckling effect. It is necessary, therefore, to prevent or at least to minimize heating of the supporting structure. This can be achieved in a simple manner as shown in FIG. 20. A terminal portion *a* of the tube 41 is coated with a thin layer 54 of highly conductive metal, such as copper or silver, which provides a shunt across the terminal tube portion and prevents heating of the same and of the associated supporting structure by the passing electric current. The tube 41 is thin enough and made of material of sufficiently poor thermal conductivity to prevent the flow of significant amounts of thermal energy through the terminal portion *a*. Heating of the support 42 by the hydraulic fluid can be held to an insignificant value by making the support 42 of alumi-

num, copper, or other highly conductive material, and by attaching it to a heat sink, such as the valve casing 26 (FIG. 17).

It should be understood, of course, that the foregoing disclosure related relates to preferred embodiments of the invention, and that it is intended to cover all changes and modifications of the examples of the invention herein chosen for the purpose of the disclosure which do not constitute departures from the spirit and scope of the invention set forth in the appended claims.

What is claimed is:

1. An electro-hydraulic transducer arrangement for converting an electric signal to a hydraulic signal, the arrangement comprising:

- a. an elongated conduit having a longitudinal wall of electrically conductive material, said wall defining a longitudinal throttling bore in said conduit;
- b. means for transmitting said electric signal to said wall, and for passing the transmitted signal longitudinally through said wall and for thereby heating said wall in response to said signal;
- c. supply means for supplying a liquid under pressure to one longitudinal end of said bore for flow of said liquid through said bore;
- d. discharge means for discharging said liquid from the other end of said bore,

1. said wall being shaped to guide said liquid through said bore in a predominantly laminar flow pattern,

2. the heating of said wall by said electric signal being sufficient to increase the temperature of the flowing liquid and thereby decrease the viscosity thereof; and

e. safety means responsive to a predetermined longitudinal, thermal expansion of said wall for interrupting transmission of said electric signal to said wall.

2. In an arrangement as set forth in claim 1, said safety means including fastening means spaced along a straight line and holding the two longitudinal ends of said conduit at a substantially fixed distance while the remainder of said conduit is offset laterally from said line in one direction, whereby said conduit buckles laterally in said one direction when expanding thermally, and switch means responsive to a predetermined amount of buckling for interrupting said transmission.

3. In an arrangement as set forth in claim 2, said switch means including a light source and a photoelectric cell arranged in the beam of said light source, said conduit interrupting said beam when buckled.

4. In an arrangement as set forth in claim 2, a coating of a highly conductive metal on said longitudinal ends of said conduit, the conduit consisting of metal having substantially greater resistivity than the metal of said coating.

5. An arrangement as set forth in claim 1, wherein said supply means include a supply conduit communicating with said one end, and said discharge means include a discharge conduit communicating with said other end, the flow sections of said supply conduit and of said discharge conduit being substantially greater than the flow section of said throttling bore.

6. In an arrangement as set forth in claim 5, said throttling bore having an effective flow section not substantially greater than 1 square millimeter.
